SUPERHEATER

Heinrich Peperkorn, Kassel-Wilhelmshöhe, Germany, assignor to The Superheater Company, New York, N. Y.

Application December 14, 1934, Serial No. 757,433
In Germany February 7, 1934

4 Claims. (Cl. 122—462)

This invention relates to superheaters for boilers of the Scotch-marine type. In one known superheater arrangement for such boilers, serpentine superheater elements are located in the return chamber and are connected to headers in the smoke-box by means of tube lengths extending through the return fire-tubes. The connecting unions are equivalent between the elements and the tube-lengths are during operation of the boiler located within the fire-tubes. When an element is to be removed it becomes necessary to disconnect the forward ends of the connecting tubes from the headers and to push the corresponding superheater element back into the return chamber until the connection comes to lie within the return chamber and is thereby made accessible. In this arrangement the superheater surface is in addition limited by the fact that sufficient space must remain free in the return chamber so that these connections can be reached after the superheater element has been pushed back.

As contrasted with this, the present invention consists in giving the superheater elements which lie within the return chamber and which are connected with the lengths extending to the superheater headers, a serpentine form a portion of which lies in the return chamber and the other portion of which extends into the tubes and is there supported. The superheater elements extend into the smoke tubes in accordance with the invention and it is therefore possible to place sufficient superheater surface into this hot zone of the smoke tubes and still to have enough space in the return chamber to make possible access to the connections between the leads from the superheater headers and the return chamber portions.

It has been suggested heretofore in the case of a superheater whose main portion lies in the return chamber, to have one or another loop extend into a smoke tube. This, however, was only done for the purpose of supporting this end of the superheater while its other end was secured to the headers which were located in the return chamber itself and which had to be inserted into the return chamber or taken out of it either through the flue or through a special opening in the rear wall. These prior cases therefore were not concerned with the superheater which has a header in the smoke box of the boiler and which has a superheater of enlarged surface in the return chamber. An arrangement in accordance with the present invention has the further advantage that the usual superheater installation which has a header or headers located in the

smoke box and has its elements lying completely within the fire tubes can readily be changed over into a return chamber superheater without discarding the header. In this way a new superheater with materially higher superheater temperatures can be supplied at relatively low cost. Even the old tube lengths extending from the superheater header into the fire-tubes and the clamps can be retained for the new superheater. It is only necessary to lengthen the tubes by welding on a piece. The new superheater can be given such form that the number of connections to the headers remains the same as in the usual smoke tube superheaters and that the connecting lengths between the superheater headers and the elements located in the return chamber remain the same for given groups of elements. A further advantageous characteristic of the new superheater is that the drop in steam pressure through the elements is kept low.

The drawings show in Fig. 1 a view partly in lateral elevation and partly in longitudinal section of a superheater in accordance with the invention; Fig. 2 is a horizontal section on line 2—2 of Fig. 1; Fig. 3 shows a fragmentary horizontal section on an enlarged scale of the return chamber portion of the superheater and boiler, the superheater being somewhat modified from the form shown in Figs. 1 and 2; Fig. 4 is a section on line 4—4 of Fig. 3; Fig. 5 is an end view looking from the left of Fig. 4; Fig. 6 shows a further variation and Figs. 7 and 8 show details.

In the form of the invention illustrated in Figs. 1, 2 and 3 the return chamber of the boiler is indicated by the reference numeral 1 and the smoke tubes by reference numeral 2. In the smoke box 3 are located the superheater headers 4. The elements of the superheater consist of separate parts 5, a portion of which as will be clear from Figs. 1, 2 and 3 lies within the return chamber 1 and the remainder of which lies within the tubes 2. The connections between the separate parts 5 and the headers 4 lying in the smoke box 3 is made by means of the pipe lengths 6 and the connecting structures or unions 7. The latter may, by way of example, be made as illustrated in Fig. 8 where the nut 8 forces the ball end connected to the length 6 into the conical end connected to the separate portion 5. This union is in a conveniently accessible point within the return chamber 1 as will be seen in Figs. 1 and 2.

The loops of each serpentine element 5 lie in a horizontal plane in the form illustrated in Figs. 1 and 2. They may, however, also lie in a vertical

plane. The loops in the form illustrated all extend the same distance into the smoke tubes but the arrangement might also be such that the return bends of the loops extend successively farther into the smoke tubes as the upper flues are approached where the gas temperature is lower. To protect the serpentine portions of the elements against direct impingement of the flame a baffle 13 is provided as shown in Fig. 1. To hold the loops of any given serpentine element rigidly in their relative position, they can be provided with distance pieces 9 (see Fig. 3).

To replace an element all that needs to be done is to break the connections 7 and to withdraw the element out of the smoke tubes whereupon it can be taken out thru the flue 12. For the insertion of an element the sequence of these steps is reversed. The connections of the lengths 6 to the headers 4 need not be disturbed. As may be seen from Figs. 1 and 2, there is sufficient space in the return chamber to make and break the connecting members 7 and in addition a sufficient superheater surface is supplied in a very effective heating gas zone i. e. at a point where the gases enter the smoke tubes.

The heating surface inside of the return chamber itself can further be augmented by giving the pieces which connect the loops lying in two neighboring smoke tubes a twisted or coiled form. In Figs. 3 to 5, for example, two turns or coils lying in horizontal planes one above the other are shown for this purpose. In the form according to Fig. 6 there are also shown two coils but these cross.

The portions extending into the smoke tubes 2 are given supports at suitable points, for example, they may be supported at the tube entrance by the supports 10 and may further be kept spaced by distance pieces 11, (see Figs. 3, 4 5 and 7).

What I claim is:

1. In apparatus of the class described, the combination of a return tubular boiler having a return chamber, a smoke box and smoke tubes connecting them, superheater headers in the smoke box, tubular superheater elements in the return chamber, each of said superheater elements comprising a plurality of parallel hair pin loops connected to form a continuous steam path, the loops each located in part in the return chamber and in part in the smoke tubes, and tube lengths, two to each superheater element, extending through smoke-tubes and connecting the ends of the elements to the headers.

2. Apparatus in accordance with claim 1, the connections between the last named tube lengths and the elements being within the return chamber.

3. Apparatus in accordance with claim 1, the tubular elements being spaced from the rear wall of the return chamber and the connections between the last named tube lengths and the elements being accessible from said space.

4. Apparatus in accordance with claim 1, the hair-pin loops of any given element being connected to each other by coils.

HEINRICH PEPERKORN.
